MEANS FOR SUSPENDING BOBBINS
IN CREEELSJohn Kenneford, Accrington, England, assignor
of one-half to Howard and Bullough Limited,
Accrington, EnglandApplication December 1, 1949, Serial No. 130,552
In Great Britain February 3, 1949

8 Claims. (Cl. 242—130)

1

The invention is concerned with the means employed for the suspension of bobbins in the creels of textile machines and in analogous situations, such means being of the known type in which a bobbin is arranged to depend upon an attachment capable of rotating upon and swinging freely about an underhung pivot fixed to the creel or the like, and in which, by a relative axial movement of the bobbin on the shank of said attachment a catch incorporated in the latter is caused to engage with, or be disengaged from, an internal shoulder or other projecting part of the bobbin; the arrangement of a suspensory attachment of this type is such that a bobbin can readily be secured to the attachment by raising it to pass over the free lower extremity of the attachment and pushing it upwardly until the catch is automatically operated to retain the bobbin in the suspended position, a successive similar upward movement of the bobbin relative to the attachment serving to disengage the catch and free the bobbin for removal.

With the object of providing an improved construction of bobbin supporting means of the said type, the present invention provides inoperative relationship to the catch, a lever capable of movement to turn the catch from the bobbin-retaining position to the inoperative position, and vice versa, and a pivoted tumbler member adapted to be impinged upon by the bobbin when the latter is moved upwardly on the attachment above the position in which it is ordinarily retained, said tumbler member reacting when so impinged upon to actuate the said lever by the gravitational effect of the tumbler with respect to its pivot so as to engage or release the bobbin from the attachment.

The tumbler member is conveniently a weighted rotatable disc mounted eccentrically and having a connection with the catch-operating lever such that, when impinged upon by the bobbin, the disc tumbles over its eccentric axis and thereby throws the catch-operating lever to rotate the catch.

The manner in which the invention may be carried into effect is hereinafter more fully described with reference to the accompanying drawings. In said drawings, Fig. 1 is a perspective view of a bobbin-suspensory attachment as seen when depending from the usual creel of a spinning or like machine, the position of a suspended bobbin being indicated in dotted lines. Fig. 2 is a vertical section through the attachment and bobbin shown in Fig. 1; and Figs. 3 and 4 are similar views to Fig. 2, respectively illustrating the positions of the parts when the

2

bobbin is raised to actuate the mechanism to release the same, and when the bobbin is offered to the shank of the attachment preparatory to its being engaged thereon.

5 It will be seen from the drawings that the attachment consists of a length of strip metal bent upon itself at its mid-point so as to form a loop 10 at one end and a pair of limbs 11, 12 which together constitute a shank upon or between which are mounted the several parts of the device as hereinafter described. The strip is pierced at the centre of the loop 10 by a hole 13 through which passes the swivel 14 of a connection to the creel, said swivel preferably incorporating a ball-bearing or other anti-friction bearing 15, the attachment being free to rotate or swing laterally from its mounting on the creel (not shown). The limbs 11, 12 of the attachment are secured together in spaced relationship, 15 primarily by the rivet 16 and distance-piece 17, and the shank formed thereby is of a thickness capable of being inserted loosely within the hollow interior of a bobbin 18.

At a point near to the lower extremity of the shank, upon a pin 19 extending between the limbs 11, 12, is a pivotal catch or detent 20 made from a plate of substantially lozenge shape. The catch 20 can rotate on said pin 19 between a position in which its major axis is disposed horizontally as shown in Figs. 1 and 2 and a position in which the apices 21, 22 of the plate at the ends of the major axis have been sufficiently withdrawn between the shank limbs 11, 12 to permit the latter to enter the hollow bore of the bobbin 18, as shown in Fig. 3. When turned into the first-mentioned position, in which the major axis is horizontal, the apices 21, 22 of the plate 20 will engage beneath the interior shoulder 23 formed at the upper end of the bore of the bobbin 18 and thereby prevent the latter from being removed from the attachment.

40 A toggle lever 24, mounted on a pivot pin 25 at an intermediate point in its length between the shank limbs 11, 12, is linked at its lower extremity with a pivot 26 on said catch-plate 20 and at its upper end said lever 24 is connected with a tumbler consisting of a weighted disc 27 pivoted upon the eccentric pin 28 in such fashion that it can rock over the axis of said pin 28 from side to side and, when so rocked, its action due to gravity will actuate the toggle lever 24 to rotate the catch-plate 20.

45 A tapered collar 29, slidable over the shank-limbs 11, 12, is arranged so as to be raised by the upper end of the bobbin 18 when this is

pushed on to the shank from below, and said collar 29 forms an abutment through which the bobbin can impinge against said weighted disc 27. It will be understood that the disc 27 hangs to one side or other of its pivot mounting 28; when impinged upon by said collar 29 on an upward thrust of a bobbin 18 as aforesaid, the disc 27 is caused to rock or tumble over the axis of the pin 28 to effect the rotation of the catch-plate 20, either into the bobbin-retaining position shown in Figs. 1 and 2, in case it is desired to suspend the bobbin from the attachment, or into the bobbin-released position shown in Fig. 3 should it be required to remove an empty bobbin for replacement by a full one. The collar 29 is prevented from sliding off the end of the shank by the projecting ends of the rivet 16. The disc 27 is of a substantial weight so that its eccentric mounting endows it with amply sufficient power to actuate the catch-operating mechanism by its gravitational effect. In an alternative embodiment (not illustrated) the disc 27 may be replaced by a suitably shaped cam or lever adapted to perform the same function.

The toggle lever 24 is appropriately slotted at 30 to receive its pivotal connection 26 with the catch-plate 20 and at 31 to receive the crank-pin 32 through which it is operated by the weighted disc; the shape of the slot 31 is preferably triangular, providing inclined surfaces 33, 34 for cooperation with the crank-pin 32 so as to enable the latter to exercise a levering action on the toggle lever 24 and thereby actuate the same when the disc 27 is rocked.

What I claim as my invention and desire to secure by Letters Patent is:

1. A bobbin suspensory attachment comprising an elongated member adapted for attachment to a creel at one end and for insertion into the hollow bore of a bobbin at the other end, a tumbler member pivotally mounted on said elongated member so as to be impinged upon and rocked about its pivot by the bobbin when the latter is moved upwardly on said elongated member above the position in which it is ordinarily retained, a catch member pivotally mounted on said elongated member and having a bobbin retaining position and an inoperative position, a lever pivotally mounted on said elongated member and capable of movement to turn the catch member from its bobbin retaining position to its inoperative position and vice versa, and a connection between said tumbler member and said lever for moving the lever in response to a rocking movement of the tumbler.

2. An attachment as claimed in claim 1 wherein the tumbler member consists of a weighted rotatable disc mounted eccentrically with respect to its pivot, so that when impinged upon by the bobbin the disc is tumbled over its eccentric pivot axis and thereby throws the said lever to turn the catch member.

3. An attachment according to claim 1 wherein the elongated member comprises a bifurcated shank of an overall thickness such that it can

pass into the hollow interior of a bobbin, the limbs of said shank being spaced apart substantially in parallelism to accommodate between them the said catch member, lever and tumbler member, pivot pins fixed through said limbs for mounting said catch, lever and tumbler on said elongated member, the shape and size of the catch being such that when turned into the inoperative position it can enter with the shank into a bobbin passed over the latter.

4. An attachment as claimed in claim 1 wherein said lever is provided with a triangular slot in its upper end, a crank pin in the tumbler cooperating with said triangular slot, said lever having a pin and slot connection with the catch.

5. An attachment as claimed in claim 1 wherein there is provided a collar freely slidable on said elongated member so as to normally rest upon an upper end of a bobbin passed over the said elongated member, said collar serving to act as a medium to actuate the tumbler member, and means for retaining the collar on said elongated member when the bobbin is removed.

6. In a bobbin suspending device, an elongated member adapted for attachment to a creel at one end and for insertion into the hollow bore of a bobbin at its other end; a catch member pivotally mounted on said elongated member; an eccentrically mounted tumbler member on said elongated member, and a link positively connecting said catch member and said tumbler member.

7. In a device of the character described in claim 6, a collar member slidably surrounding said elongated member.

8. In a device for detachably supporting a bobbin, a bifurcated member adapted for attachment to a creel, the shanks of said member being adapted for insertion into the hollow bore of a bobbin, a headed pin for connecting the lower ends of said shanks, a catch pivotally mounted between said shanks above said pin and adapted to prevent removal of said bobbin from said member in one position and to permit removal of said bobbin in a second position, a lever pivotally mounted between said shanks above said catch, a disc eccentrically mounted between said shanks above said lever, said lever being connected at its lower end to the said catch and at its upper end to said disc, a collar mounted on said shanks for restricted sliding movement thereon, said movement being restricted upwardly by notched portions on said shanks and downwardly by said headed pin, said collar when resting on said pin engaging said catch to retain the same in said second position.
